UNITED STATES PATENT OFFICE.

LEON P. LOWE, OF SAN FRANCISCO, CALIFORNIA.

PROCESS OF PRODUCING COKE AND GAS FROM FLUID HYDROCARBON.

1,174,511.

Specification of Letters Patent.

Patented Mar. 7, 1916.

Application filed April 29, 1914. Serial No. 835,161.

To all whom it may concern:

Be it known that I, LEON P. LOWE, a citizen of the United States, residing at San Francisco, in the county of San Francisco and State of California, have invented new and useful Improvements in Processes of Producing Coke and Gas from Fluid Hydrocarbon, of which the following is a specification.

10 The object of my invention is to provide a method of simultaneously producing coke and gas from petroleum, or other fluid hydrocarbons, including natural gases.

15 In the accompanying drawing, Figure 1 is a vertical section of an apparatus for carrying out my improved process; Fig. 2 is a similar view of a modification thereof.

Referring to the drawing, 1 indicates a metal shell having a brick lining 2. Extending transversely across said shell are horizontal series of arches, namely, a lower series of arches 3 to support the solid constituents recovered from petroleum, an intermediate series of arches 4 above said solid 25 constituents to protect them from the agitating action of air introduced above the arches 4 during the reheating step of my improved process, and an upper series of arches 5, which support checker brick-work 6 extending upwardly to within a short distance of the top of the shell. Upon said shell 1 is erected a stack 7, and products of combustion from the interior of said shell discharge into said stack through an opening in the 30 top of the shell controlled by a valve 8. The stack 7 is not, however, a necessary part of the apparatus, and can be dispensed with if preferred to supply air by forced blast.

40 Leading into the space 9 between the top of the shell and the top of the checker brick-work are valve-controlled oil conduits 10, and pipes 11 for admitting preferably compressed combustible gas to assist in atomizing or spraying the fluid hydrocarbon. Into the space 12 between the upper arches 5 and the intermediate protective arches 4 oil or gas is admitted by valve-controlled burners or atomizers 13 and air is admitted by valve-controlled air conduits 14. Access is had to 45 the space 15 immediately above the lower arches 3 by charging and discharging doors 16. Into the space 17 between the lower arches and the bottom of the apparatus air can enter by a valve-controlled conduit 18 and gas can automatically escape by an outlet 19 leading to the usual seals, washers,

condensers and the like. Access is also had to said space by a cleaning-out door 20.

In carrying out my improved process, a shallow layer of coke, coal or other suitable 50 carbonaceous substance is placed on the lower arches 3, ignited, and brought to a high degree of heat by an air blast admitted through the air conduit 18. Simultaneously air is admitted by the conduits 14 and the 55 checker brick-work 6 above the upper arches 5 is highly heated by the combustion of oil or gas admitted by the burners 13, all the products of combustion escaping through the valve 8. When the checker brick-work 6 60 has been sufficiently heated, probably from 1600° to 2200° F. the burners 13 are closed, the air blasts through the air conduits 14 and 18 are shut off, and the valve 8 is closed. The conduits 10 and 11 are opened and oil or 65 other suitable fluid hydrocarbon is then atomized or sprayed, either by direct pressure or compressed combustible gas, into the space above the checker brick-work 6, through which it passes downwardly. In 70 so passing the atomized hydrocarbon is, more or less completely, "broken down" into hydrogen and carbon, the latter assuming the solid form known as lamp black. This mixture of hydrogen and carbon, with 75 residual tarry hydrocarbons if any, then passes down through the bed of incandescent fuel on the lower arches 3, which fuel bed filters out and retains the solid carbon and still further "breaks down" the residual hydrocarbons into carbon and gas, the gas passing through the fuel bed, and through the 80 lower arches, escaping from the apparatus at the gas outlet 19, from which it passes to the customary seal, cooling apparatus, condensers, container, or point of consumption. 85

The complete separation of fluid hydrocarbon into hydrogen and carbon is scarcely practicable in the checker brick-work 6 alone, certain constituents of the hydrocarbon going forward therefrom in the form of a heavy, tarry hydrocarbon, which heavy substance is, however, "broken down" in passing through the zone of the fuel bed on the lower arches 3, heated more highly than 90 is practically possible in the checker brick-work 6 alone, this highly heated zone separating practically all the hydrogen and carbon, the latter being retained in the fuel bed in the form of coke, the bed gradually increasing in depth. When a sufficient amount 95 of coke has accumulated, it is removed, and 100 105 110

the process is repeated. This process of accumulating the coke cannot, however, be carried on continuously. The heat of the checker brick-work 6, must be restored from time to time to a temperature sufficient to cause the partial "breaking down" of the hydrocarbon in the checker brick-work 6, and the heat of the lower fuel bed must likewise be restored to a temperature sufficient to cause its final "breaking down" as completely as practically may be. Consequently, after the "breaking down" has been continued for the proper length of time, the conduits 10, 11 are closed, the valve 8 is opened, the air blasts through the conduits 14 and 18 are set in action and the burners 13 are opened. Only a relatively small amount of air is admitted below the fuel bed to keep it in a sufficiently highly heated state to perform its function, with the combustion of a very small percentage of said fuel. During the step of reheating the checker brick-work 6, the protective arches over the coke chamber serve the purpose of preventing the combustion and agitation of the coking fuel. Any gases that have arisen from the coking fuel are, in the reheating stage, burnt, and thus assist in the reheating of the checker brick-work; whereas during the coking step, they pass downward and are separated into carbon and hydrogen. After the checker brick-work and the fuel bed have been restored to the proper temperature, the step of "breaking down" the fluid hydrocarbon is repeated. Should any tarry residue or lamp black escape through the gas outlet 19, it will be retained in, and recovered from, the gas washing, condensing and cooling devices, and returned to the apparatus from time to time with other fuels, until the gasification and carbonization of the original hydrocarbon are finally completed. If it is desired so to do, other carbonaceous fuel can also be used for the production of coke in conjunction with that derived from the fluid hydrocarbons as described. If it is not desired to otherwise use the produced gas, it can be returned to the apparatus and used to heat the checker brick-work 6.

I do not regard it essential to the success of my process that the hydrocarbon should be completely separated into carbon and hydrogen, as the process will be of sufficient utility even though, as will probably be the case, the resulting gas contains a certain amount of hydrocarbon gases.

The radiant heat from the arches over the coking chamber is an important factor in the coking process, the action being the same as when coke is made from coal by the well known "bee-hive" process.

The operation of the apparatus with varying results can be modified by atomizing the hydrocarbon with steam, or with air, or with a mixture thereof, under which conditions a portion of the fuel in the coking chamber will be consumed in converting the steam and air into a combustible gas. If preferred, flue channels can be used instead of the arches 3 to support the coking fuel. When the apparatus is operated in a highly heated condition it can be used for the manufacture of commercial hydrogen suitable, for instance, for inflating balloons or air ships.

In the modification of the apparatus illustrated in Fig. 2, the arches 4, 5, checker brick-work 6, air conduits 14, and burners 13 are dispensed with, and a gas burner 23 is preferably supplied leading into the space 17. With this apparatus, a shallow layer of coke, coal or other suitable carbonaceous substance placed on the arches 3, is ignited by the gas burner 23 or otherwise, and brought to a high degree of heat as before. Oil is then admitted and sprayed, as before, into the chamber in the upper part of the shell, but it now passes directly into the bed of incandescent fuel on the arches 3. It then passes through said fuel bed, and in so passing is "broken down" into hydrogen and carbon, the gas passing through the bed, and through the arches, and escaping as before, the carbon being retained in the fuel bed in the form of coke, the bed gradually increasing in depth. When a sufficient amount of coke has accumulated, it is removed, and the process is repeated. The heat of the fuel bed must be restored from time to time, as before, to a temperature sufficient to cause the breaking down of the oil.

I claim:

The process of obtaining coke and combustible gas from fluid hydrocarbon which consists in heating to incandescence a bed of solid fuel, passing thereto finely divided fluid hydrocarbon, thereby breaking down the hydrocarbon into hydrogen and carbon, drawing through said bed the hydrogen only and leaving thereon a deposit of carbon, admitting to the carbon thus deposited an amount of air sufficient only to consume part only of said deposited carbon, and repeating the part of the operation subsequent to the first-named step.

In testimony whereof I have hereunto set my hand in the presence of two subscribing witnesses.

L. P. LOWE.
